UNITED STATES PATENT OFFICE

130,496

DESIGN FOR A POPCORN DISPLAY AND DISPENSER CABINET OR SIMILAR ARTI- CLE

Thomas V. Atkins, Burlington, Mass., assignor to
Harvey C. Wheeler, Brookline, Mass.

Application March 25, 1941, Serial No. 99,868

Term of patent 7 years

To all whom it may concern:

Be it known that I, Thomas V. Atkins, a citizen of the United States, residing at Burlington, in the county of Middlesex, in the Commonwealth of Massachusetts, have invented a new, original, and ornamental Design for a Popcorn Display and Dispenser Cabinet or Similar Article, of which the following is a specification, reference being had to the accompanying drawing, forming a part thereof.

Figure 1 is a perspective view of my popcorn display and dispenser cabinet, showing my new design, and Figure 2 is a rear elevational view of the same.

I claim:

The ornamental design for a popcorn display and dispenser cabinet or similar article, substantially as shown.

THOMAS V. ATKINS.
